CLAIM

The ornamental design for a split top backpack, as shown and described herein.

DESCRIPTION

FIG. 1 is a front elevation view of the split top backpack; FIG. 2 is a rear elevation view of the split top backpack; FIG. 3 is a right side elevation view of the split top backpack; FIG. 4 is a left side elevation view of the split top backpack; FIG. 5 is a top view of the split top backpack; FIG. 6 is a bottom view of the split top backpack; FIG. 7 is a right side perspective view of the split top backpack; FIG. 8 is a left side perspective view of the split top backpack; FIG. 9 is a front perspective small interior top view of the split top backpack; and, FIG. 10 is a front perspective large interior top view of the split top backpack. The broken lines on and adjacent to unshaded surfaces depict portions of the split top backpack and form no part of the claim. The broken lines on surfaces with surface shading depict stitching and zipper track and form no part of the claim.
